(57) **CLAIM**

We claim the ornamental design for the automotive clutch diaphragm spring, as shown and described.

DESCRIPTION

FIG. 1 is a top plan view of the automotive clutch diaphragm spring;

FIG. 2 is a side perspective view of the automotive clutch diaphragm spring; and,

FIG. 3 is a bottom plan view of the automotive clutch diaphragm spring.

The broken lines are shown for illustrative purposes only and form no part of the claimed design.
